DESIGN FOR A TWO-PIECE BEACH SUIT

Gay S. Walton, New York, N. Y., assignor to Julius
Kayser & Co., New York, N. Y., a corporation
of New York

Application October 5, 1935, Serial No. 58,852

Term of patent 3½ years

To all whom it may concern:

Be it known that I, Gay S. Walton, a citizen of the United States, residing at 56 Seventh Avenue, in the city, county, and State of New York, have invented a new, original, and ornamental Design for a Two-Piece Beach Suit, of which the following is a specification, reference being had to the accompanying drawing, forming part thereof.

Figure 1 of the drawing is a plan view of the top or bust part, and Figure 2 is a plan view of the lower or trunk part of a beach suit embodying

my new design; the top part being characterized by a knot between the two similar triangular pieces, and the bottom part by two similar knots located where the front and back pieces join near the waist line. The back of the bottom part is substantially identical to the front.

I claim:

The ornamental design for a two-piece beach suit, as shown and described.

GAY S. WALTON.
